UNITED STATES PATENT OFFICE.

JOHN P. HAMILTON, OF MILWAUKEE, WISCONSIN, ASSIGNOR, BY MESNE ASSIGNMENTS, TO ALLIS-CHALMERS MANUFACTURING COMPANY, OF MILWAUKEE, WISCONSIN, A CORPORATION OF DELAWARE.

FILTER-PRESS BAG.

Application filed April 4, 1923. Serial No. 639,810.

The present invention relates to improvements in metallic filter press bags and particularly to bags for use in a press of the general type shown in U. S. Patent 5 1,336,341, granted April 6, 1920 to John J. Berrigan.

The general purpose of the invention is to provide a metallic filter press bag of such construction that a plurality of them can be 10 used in a press without separators or racks between them, or at most with only a plain sheet of metal as a separator, the construction being such that there will be no inaccessible or difficultly accessible spaces to 15 receive and retain sediment or dirt of any kind. With a press bag made in accordance with this invention, all parts may be cleaned readily so as to keep the apparatus in sanitary condition, while at the same time 20 the press pressure is readily transmitted from the wall of one bag to the adjacent wall of the adjacent bag and properly distributed to the contents of the bag, thus giving a durable bag.

As presses of the type described and with collapsible metallic bags are coming into general use for filter-pressing organic materials of a putrescible nature, it becomes important in many cases to have the press 25 and bags in a thoroughly sanitary condition at all times during the operation. This is difficult and even impossible to accomplish if there are any inaccessible or difficultly accessible pockets or spaces into 30 which germs may enter and remain. With the present invention a structure is provided in which there are no such pockets or spaces and therefore the danger of contaminating the material being treated is materially 35 reduced.

A further object of the invention is to provide a simple and durable press bag.

With these general objects in view, the invention consists in the features, details of 40 construction and combination of parts which will first be described in connection with the accompanying drawings and then more particularly pointed out.

In the drawings,—

Fig. 1 is a side elevation, partly broken away, of a bag embodying the invention;

Fig. 2 an end view of the same;

Fig. 3 an enlarged sectional view, partly broken away, the section being taken on the line 3—3, Fig. 1;

Fig. 4 a horizontal section on the line 4—4, Fig. 1;

Fig. 5 a detail sectional view, illustrating the locking mechanism;

Fig. 6 a detail view of one corner of a 60 bag;

Fig. 7 a detail view showing two bags adjacent to each other in place in a press;

Fig. 8 illustrates the general type of press with which the bags are intended to be 65 used;

Fig. 9 is a detail view showing a modified form of the invention; and

Fig. 10 illustrates a separator between 70 two bags.

Referring to the drawings, A¹, A² are the side frames of the bag. Each side frame comprises top and bottom rails 1 and 2 respectively and stiles 3, made of heavy sheet metal. While these frames may be stamped 75 out of one sheet of metal of the desired thickness, it is generally more economical to use strips of metal of the requisite widths and then weld these strips together to form the frame. In practice the stiles are butt-welded to the rails by electric or oxy-acetylene welding. In the embodiment of the invention shown, the stiles are considerably wider than the rails.

For the purpose of suitably hanging the 80 filter bag in the press, the top rails 1 are extended beyond the stiles and bottom rails, as shown in Fig. 1, each overhanging end of the top rail being provided with a slot, as indicated at 4, and also with a block 5, riveted to the top rail and having a downward-extending portion arranged to engage 85 the inner face of the main supporting rail 6 of the press.

To each frame is secured a panel plate 90 B of suitable metallic foraminous material. In the best embodiment of the invention, this plate is of sheet metal which has that portion over the frame-opening suitably perforated. In practice it is well to have the 95 panel-plate of such dimensions that its edges will be substantially flush with the edges of

the frame. In the embodiment of the invention illustrated in Figs. 1 to 7, the panel-plate is secured to the outer face of its respective frame. In the construction shown 5 in Fig. 9, the panel plate is secured to the inner face of its frame.

On the outer face of each bag-wall there is arranged a plurality of pressure-transmitting bars, indicated at C. In the best embodiment of the invention, these bars are 10 rectangular in cross-section and are arranged vertically, each bar having one of its narrow faces in contact with the panel-plate. The bars C have a length somewhat 15 less than the height of the frame, but sufficient to allow them to be riveted to the top and bottom rails. These bars are spaced apart sufficiently to allow a proper discharge 20 of liquid from the material in the bag, while at the same time, the bars must be close enough to properly sustain the perforated metal so that it will not sag too much between the bars, when subjected to the pressure of the materials which are being 25 pressed.

In the construction shown in Figs. 3 and 4, each bar has the same width or depth throughout its length. In the construction shown in Fig. 9, each bar is notched into 30 the frame so its inner face may touch the panel-plate and support it.

The side walls of the bag, formed by the two frames and their panel plates, are connected at the sides by collapsible end members. In the best embodiment of the invention, each end member comprises two leaves, D, D¹, hinged together along their meeting edges, and also hinged to fixed leaves d, d¹, respectively, secured to the 35 corresponding frame, as shown in Fig. 4. Each of the fixed leaves, d and d¹, is secured to the frame by rivets which pass through the leaf, through the corresponding stile, and through the corresponding 40 panel-plate, some of the rivets also passing through the corresponding vertical pressure bar at that end of the bag. Each collapsible end member also has the upper end of its two leaves sloped in opposite directions from 45 the center to form an inverted V or gable, as will be clear from Fig. 3.

The bag is provided with a collapsible top, which comprises leaves E and E¹ hinged to fixed leaves e and e¹ secured to the 50 respective top rails of the corresponding frames, and locking means for holding the two leaves together. In the present instance the locking means comprises a suitable locking strip e², which is advantageously 55 an angle-iron strip having one flange turned outward and the other riveted to its leaf. This locking strip is arranged to be engaged by a series of hooks e³ fixed on a rotatable rod e⁴ journaled in bearings e⁵ riveted to 60 the downward-turned flange of an angle-

iron strip e⁶ having its other flange hinged to the leaf E¹. The rod e⁴ has its ends extended beyond the back and cranked to form handles by which the rod may be rotated by the operator, as shown in Fig. 1. The 70 hooks may be turned so that their ends project through slots cut in the angle-iron strip e⁶ and bear against the edge of the vertical flange of the locking strip e², as shown in Fig. 5. This will lock the bag 75 against the internal pressure of the materials.

The rivets which hold the fixed leaves d, d¹ to the corresponding frames pass through the corresponding top rails and 80 through the corresponding panel plates.

The inside of the bag near the bottom is provided with suitable sealing means, as, for example, the two sealing bars F, Fig. 3, one for each side of the bag. These bars 85 are riveted to the respective lower rails, the rivets passing through the panel plates. It is advisable to bevel or chamfer these bars on their upper surfaces so that the press cake may easily be discharged from 90 the bag.

When a collapsible bag of the type described is used in a press of the type disclosed in Patent 1,336,341, as shown in Fig. 8, the bottom of the bag is collapsed to 95 close it, while the top is still open, so that the side members of the bag slope toward each other from the top to the bottom. In order to permit this to be done without injury to the end members D, D¹, the latter 100 have leaves of such width that the metal of the leaves may be twisted or distorted, due to the variation in the opening of the different parts of the bag, without exceeding the elastic limits of the metal. In practice 105 the desired result above mentioned will be insured by making the width of each leaf of an end member greater than the widest opening of the bag.

In operation, a plurality of bags are used. 110 The outer faces of the pressure-transmitting bars C of one side wall of a bag register or contact with the faces of the bars C on the adjacent wall of the adjacent bag. When the bags are filled with material to be pressed and their top closures locked, the pressing operation may begin. The liquid expressed 115 from the bag through the openings in the side wall will flow down readily through the discharge channels formed by the spaces between the bars C. As the press squeezes the bags, there is a tendency to a slight shifting 120 of the bags with relation to each other, usually in a vertical plane. This may cause a slight wear of the bags against each other, but this wear is confined to the outer faces of the pressure-transmitting bars C of each frame, and does not in any way affect the platen-plates B of the bags. Hence, for this 125 reason the bags are more durable than would 130

be the case where separators or racks were employed which contacted directly with the panel-plates. It is obvious that the bags may be cleaned readily, there being free access to the drainage channels between the bars when the bags are separated.

The locking device for the top closure will be found very efficient in resisting the internal pressure of the material in the bag, and yet may be readily released when the bag is to be opened. On account of the hinge-joint between the locking member and the leaf E¹ to which it is attached, the top-closure approximately fits the gable or pointed ends of the end-members at all conditions of the bag, thereby preventing the escape of material over the ends of the bag as the press closes.

If desired, a separator may be inserted between the bags, but in this case the separator can be merely a flat sheet of metal as indicated at f, Fig. 10, having lugs f¹ at the top which serves to prevent the sheet from dropping to the floor when the press is opened. As soon as the press closes the separator is held by the pressure of the bags against it. Such a separator may readily be removed and cleaned as it does not have any inaccessible pockets to trap the dirt. It will be understood that the bags are suspended in the press by their top rails 1, which rest on the usual supporting bars 6, carried by the press. The bags are spaced apart in any desired way, as, for example, by chains 7 which may have certain of its links inserted in the slots 4 of the top rails

1. The filling, pressing and emptying of the bags takes place in the usual way in presses of this type.

It will be observed that in the construction hereinbefore described, the metallic filter press bag is provided with a separator device on each side, these separator devices being a permanent part of the bag. Furthermore, these separator devices are of such construction as to form open channels, readily accessible for cleaning when the bag is out of the press. The pressure-transmitting members, or bars, which produce the channels between each pair of such members not only serve to take the wear due to the sliding of one bag relative to the other, as hereinbefore described, but also serve to stiffen the bag frame to which they are riveted.

What is claimed is:

A filter-press bag unit comprising interconnected foraminous metallic side walls each having a plurality of pressure-transmitting bars permanently attached to the unit at the wall edges and spaced apart to provide external outwardly open drainage channels directly upon the unit, said bars being formed for coaction with similar bars of an adjacent unit to prevent outward distortion of said walls at said bars and to form unobstructed open ended conduits extending entirely across the adjacent sides of the cooperating units.

In testimony whereof, I have hereunto set my hand.

JOHN P. HAMILTON.
